ATTORNEYS.

UNITED STATES PATENT OFFICE

2,425,708

CONTAINER

Isaac L. Wilcox, Fulton, N. Y., assignor to
 Oswego Falls Corporation, Fulton, N. Y., a corporation of New York

Application August 18, 1944, Serial No. 550,057

2 Claims. (Cl. 229—5.5)

1

This invention relates to containers formed of sheet material such as paperboard, and has as an object an end closure structure which is particularly strong and durable, whereby the container, although formed of relatively low strength material, will effectively withstand rough handling, dropping, etc.

The invention consists in the novel features and in the combinations and constructions hereinafter set forth and claimed.

In describing this invention, reference is had to the accompanying drawing in which like characters designate corresponding parts in all the views.

Figure 1 is a side elevational view of a container embodying my invention.

Figure 2 is a top plan view of the container shown in Figure 1.

Figure 3 is a fragmentary sectional view of the top portion of the container taken on line 3—3, Figure 1.

The body 10 of the container is of tubular formation, rectangular in cross section, and is provided with a suitable bottom end closure 11. The top closure 12 is formed about its periphery with an inverted channel 13 adapted to receive the end edge of the body 10 and enclose the same. The channel 13 is sealed to the end of the body. Usually, if the container is formed of fibrous material, such as paperboard, at least the interior of the body and the inner surface of the closure 12 and channel 13, and preferably the exterior surfaces thereof as well, are coated with an impervious, heat-sealing material which renders the container impervious to moisture and this coating, at the same time, affords a convenient means of permanently sealing the inner and outer walls of the channel 13 to the top edge of the body.

The sides of the channel formation adjacent each corner are pressed or pinched together to form corner ribs 15. If the outer surface of the end closure is coated with the thermoplastic material, this pressing action is done with heated

tools, whereby the portions of the channel pressed together to form the ribs 15 are permanently secured together. The channel 13, intermediate the corners, is inclined inwardly as at 16.

This arrangement forms a truss structure which is strong and rigid and affords particularly good protection at the corners of the end closure which, with ordinary construction, often open up or leak in the event the container is dropped after it has been filled with liquid, or other heavy contents.

What I claim is:

1. A container formed of sheet material comprising a tubular body of rectangular cross section, an end closure formed at its periphery with an uninterrupted inverted channel enclosing the end portion of the body and being sealed thereto, the sides of said channel adjacent each corner being pressed together to form a corner rib, and the channel intermediate the corners being inclined inwardly.

2. A container formed of sheet material comprising a tubular body of rectangular cross section, an end closure formed at its periphery with an uninterrupted inverted channel enclosing the end edge of the body and being sealed thereto, the sides of said channel adjacent each corner being pressed together and sealed to form a corner rib, and the channel intermediate said corners inclining inwardly.

ISAAC L. WILCOX.
